MECHANICAL FIGURE SIMULATING POURING AND DRINKING LIQUID

Milton Adler, New York, N. Y.

Application April 3, 1948, Serial No. 18,801

15 Claims. (Cl. 46—141)

1

This invention relates to a mechanical toy which operates to simulate a child drinking milk.

An object of this invention is to provide a mechanical toy comprising a base, a table simulating member on the base, a chair simulating member on the base, a body simulating member on the chair in front of the table and including a movable arm simulating portion holding a glass above the table, and another arm simulating member holding a bottle above the table, and a head simulating member pivoted to the body simulating member.

Another object of this invention is to provide a mechanical toy of the character described operated by a spring motor and having provisions for lifting the arm simulating member holding the glass to raise the glass to the mouth of the head simulating member, and provisions for tilting the bottle toward the glass when the first arm simulating member is down.

Yet a further object of this invention is to provide a mechanical toy of the character described having a mechanical action which simulates filling a glass of milk from a bottle, bringing the glass up to the mouth of the head of the toy, emptying the glass, bringing the glass down and refilling it.

Still another object of this invention is to provide a mechanical toy of the character described, in which the head simulating member is pivoted to the body of the toy, a spring being provided to resiliently resist backward tilting of the head, whereby when the first arm simulating member raises the glass into contact with the mouth, the head will be tilted against the spring, and when said arm comes down again, the spring will push the head forwardly again to normal position.

Still another object of this invention is to provide a strong, rugged, durable and amusing toy of the character described, which shall be relatively inexpensive to manufacture, which shall be easy to assemble, smooth and positive in operation, attractive in appearance, and practical and efficient to a high degree.

Other objects of this invention will in part be obvious and in part hereinafter pointed out.

The invention accordingly consists in the features of construction, combinations of elements, and arrangement of parts, which will be exemplified in the construction hereinafter described, and of which the scope of invention will be indicated in the following claims.

In the accompanying drawings in which is shown various illustrative embodiments of this invention,

2

Fig. 1 is a side elevational view of a toy embodying the invention and showing the forearm simulating member holding the glass, in downward position;

5 Fig. 2 is a front elevational view of the toy shown in Fig. 1;

Fig. 3 is a top plan view of the toy shown in Fig. 1;

10 Fig. 4 is a partial side elevational view showing the forearm holding the glass in partly raised position;

Fig. 5 is an enlarged side elevational view illustrating the forearm simulating member holding the glass and operating parts therefor;

15 Fig. 6 is a cross-sectional view taken on line 6—6 of Fig. 1;

Fig. 7 is a cross-sectional view taken on line 7—7 of Fig. 5;

19 Fig. 8 is a cross-sectional view taken on line 8—8 of Fig. 6, and

20 Fig. 9 is a cross-sectional view taken on line 9—9 of Fig. 6.

Referring now in detail to the drawing, 10 designates a toy embodying the invention. The same comprises generally a base 11, a table simulating member 12 thereon, and a chair simulating member 13 on the base and spaced back of the table.

The toy 10 further comprises a child's toy figure 14 comprising a body simulating member 15 and a head simulating member 16 mounted thereon. The body simulating member 16 comprises right and left arms 17 and 18 fixed thereto, a right forearm 19 movably connected to the right arm 17, a glass 20 held by the forearm 19, a left hand simulating member 21 rotatably mounted on the arm 18 and attached to a bottle simulating member 22.

The base 11 may be provided with legs or downwardly depressed flanges 25. The top wall 26 of the base is formed with four holes 27 at the front part thereof and four holes 28 at the rear part thereof. The table simulating member may be made of stamped sheet metal or any other suitable material. It may comprise a table top 30 and four corner legs 31. Extending from the lower ends of the legs 31 are tongues 32 passing through the openings 27 and bent over to engage the underside of the top wall 26 of the base for fixing the table simulating member to the base. The table top 30 is formed with a vertical through opening 32 at about the center thereof, and with a second through opening 33 closer to the right side thereof. Also there is attached to the underside of the table top 30, a pair of apertured ears 34 carrying a transverse

40 flange 35.

45

50

55

pivot pin 35 for the purpose hereinafter appearing.

The chair 13 may be made of sheet metal or may be of any other suitable construction. It comprises a seat 36 supported by vertical legs 37 and a chair back 38 extending upwardly from the seat. The legs 37 may be formed with tongues 38 projecting through the openings 28 and bent back against the underside of the top wall 26 of the base 11 for fixing the chair to the base.

The body 15 may be made of stamped sheet metal. It may be made of two parts attached together along a vertical plane passing through the middle of the body. The two parts are hollow and substantially symmetrical. One of the parts may be formed with a plurality of holes or slots 40 to receive tongues 41 extending from the other body part, at the split, said tongues being bent over to attach the two parts together in accordance with the usual practice in attaching together hollow stamped sheet metal toy parts.

The body 15 may be attached to the chair in any suitable manner and the figure appears to be sitting on the chair. The body comprises a trunk portion 42 and legs 43 and is formed with an open neck portion 44. The legs may project beneath the table and include shoe simulating portions 46 which may contact the top of the base 11. The body 15 carries at the neck, a transverse horizontal pivot pin 47 which may pass through suitable openings in the body or may be fixed to the body in any suitable manner.

The head simulating member 16 is hollow and may comprise two parts attached together in any suitable manner. The head 16 includes a neck 48 which projects through the neck opening 44. The pivot pin 47 passes through openings in the neck 48 so that the head is pivoted to the body for oscillation. Attached to the inner side of the front of the body, as by rivet 49, is a leaf spring 50, which contacts the underside of the rear of the neck 48 and tends to tilt the head forwardly or in a clockwise direction looking at Fig. 1 of the drawing, to keep the head in upright position. The front of the neck contacts the front edge 52 of the neck opening to limit movement of the head to upright position.

The right arm simulating portion 17 may be fixed to the body in any suitable manner. It comprises a hollow metal shell which is inclined downwardly and forwardly. The body 15 is formed with an opening 54 adjacent the lower end of member 17. The lower end of member 17 is open. Said member 17 has an outer wall 17a, which carries adjacent its lower end, a downwardly and forwardly inclined pivot pin 55, located in a vertical plane parallel to the front or rear legs of the table 12. Member 17 is formed with a slot 17b to permit forearm member 19 to swing upwardly. The forearm member 19 comprises a hollow tube having extension 56 pivoted to the pivot pin 55, the arrangement being such that as the forearm simulating member swings upwardly, its forward end will move upwardly and toward the vertical mid section of the body to a point in front of the mouth 16a of the head 16. Extending from the forward end of the forearm simulating member 19 is a hand simulating member 57, which is fixed to the glass simulating member 20 in any suitable manner. The member 20 is made of transparent material, such as glass or synthetic plastics.

The top open end of the glass 20 is closed by a cover 20a which may be fitted thereon in any

suitable manner, such as by friction, and is formed with an opening 59 located adjacent the front of the rim of said cover. The band simulating member 57 may be pressed around the lower end of the glass. Said glass 20 is furthermore formed with an opening 60 adjacent its lower end communicating with the interior of the hollow hand simulating member 57.

Means are provided to support the glass 20 when the glass is in its lowermost position as shown in Fig. 1 of the drawing. To this end, there is pivoted to the pin 35, a lever 61. Pivoted to an intermediate portion of the lever 61 as at 62, is a rod 63, passing upwardly through the opening 33 in the table top. Supported at the upper end of the rod 63 and above the table top, is a disc 64 on which the glass 20 may rest when said glass is in its lowermost position, as shown in Fig. 1. Attached to the underside of the table in any suitable manner is one end of a leaf spring 66 contacting the underside of the lever 61 and biasing said lever upwardly to swing in a counterclockwise direction looking at Fig. 2 of the drawing. The spring 66 may be attached to the underside of the table top 30 by means of a rivet 67 or in any other suitable manner. When the glass comes down its weight will depress the lever 61 against tension of spring 66, thereby lowering said lever to the position of Fig. 2.

Pivoted to the outer end of lever 61, as at 68 is a vertical rod 69. It will be noted that the lever 61 is inclined downwardly and rearwardly. The rod 69 passes upwardly through the opening 32 in the table top 30, for the purpose herein-after appearing.

Mounted on the table top 30 is a U-shaped bracket 70 having a pair of upwardly extending arms 71. The arms 71 are located in a vertical plane inclined rearwardly and outwardly. Hinged to the upper ends of the arms 71 as on pivot pins 72, is a milk bottle simulating member 22.

The upper end of rod 69 is pivoted to the milk bottle simulating member 22 as on hinge 74 spaced from hinges 72.

It will now be understood that when the glass 20 comes down and depressed rod 63 swings lever 61 downwardly, rod 69 will pull down the bottle 22 and cause the same to swing in a counterclockwise direction, looking at Fig. 2, about the hinges 72, thereby bringing the mouth 73a of the bottle to a position above the top of the glass 20. When the forearm 19 is raised in a manner hereinafter to be described, thereby moving the glass 20 off the disc 64, spring 66 will raise the lever 61, thereby raising rod 69 and causing the milk bottle 22 to swing in a clockwise direction toward vertical position about the hinges 72.

Mounted within the hollow body 15 is a spring motor frame 80 having a front wall 81, a rear wall 82, and side walls 83. The front and rear walls 81 and 82 have extensions 81a and 82a formed with tongues 81b and 82b, which pass through suitable openings in one side of the body, said tongues being bent over for attaching the frame 80 to the body. Disposed within the frame 80 is a spring motor 85. The same comprises a torsion spring 86, the outer end of which is attached to the rear wall 82, as at 87. The inner end of the spring is fixed as at 88, to a winding stem or shaft 89. The stem 89 passes through an opening 90 in the body and is provided with a handle 91. Fixed on shaft 89 is a pawl 92 having a pair of spring fingers 93 the ends of which project toward and press against a face of a

pinion 96 rotatable on shaft 89. Said pinion 96 has an annular series of spaced holes 95 engageable by fingers 93. Said pinion 96 meshes with a pinion 97 mounted for rotation on the frame. Pinion 97 rotates another pinion 98 journaled in the frame, which in turn meshes with the pinion 99 fixed to a crank shaft 100 parallel to the shaft 89 and journaled in the frame. Journaled in the frame is a pinion 100a meshing with pinion 98. Fixed for rotation with said pinion 100a is an eccentric weighted member 100b serving as a governor in the well known manner to regulate the speed.

It will be noted that when the spring is wound by turning the winding shaft 89, the gear train does not rotate as the fingers 93 merely click over the holes 95. However, when the shaft 89 is released, the fingers 93 will engage the holes 95 and rotate the gear train for rotating the crank shaft 100.

Fixed to the crank shaft 100 is a cam member 101 having a pair of oppositely disposed cams 102. The crank shaft 100 is formed with an offset arm 103 formed with a finger 104 connected by link 106 to a pivot 107 on the forearm 19 and above the pivot pin 55.

It will now be understood that as the crank shaft 100 rotates, forearm 19 will be caused to oscillate up and down about the pivot pin 55, and the glass will be brought back and forth from the disc 64 to the mouth of the head.

Connected to the opening 59 in the glass 20 is one end of a rubber or resilient hose or tube 110 which passes through the hand simulating member 57 through the forearm simulating member 19 and through the opening 54 and is wound several times around the frame 80 and within the body 15.

The tube extends to a position above the cover of the glass when said glass is in down position. It extends to a height which provides an internal volume equal to the glass volume as shown in Fig. 1 so that when the glass is lifted, all of the liquid in the glass may pass to and be wholly contained in said tube. The tube may be attached within the body by any suitable brackets or clips and its upper end is open.

Attached to the rear wall 82 of the frame 80, as at 112 is one end of a spring 113. The spring 113 has an offset downwardly curved arm 114 which is disposed above a portion of the tube 110, adjacent the opening 54. Furthermore, the curved portion 114 of the spring is disposed above the cam arms 102. The arrangement is such that as the crank shaft rotates, the crank arms or cams 102 will alternately contact the underside of spring portion 114 to successively raise the same. As each crank arm passes beyond said portion 114, said portion will move down and pinch or close the tube 110. Attached to one of the frame walls 83 is a horizontal wall or platform 83a on which a portion of the tube 110 lies. When the crank cam 102 is not lifting the spring 114 of spring 113, such portion 114 is pressing the tube against the platform 83a to constrict and close the tube against the passage of liquid therethrough. However, when either cam 102 engages spring portion 114, the spring is raised and the tube is opened. It will thus be seen that for each revolution of the crank shaft 100, the forearm 19 together with the glass 20 are lifted and lowered, and also the two cams 102 successively lift spring 113, so that the tube is released twice. The cam pins 102 are so arranged that the spring 113 is lifted when the arm 19 is approaching its

lowermost position and when said arm is approaching its uppermost position.

As stated above, the arm 18 may be fixed to the body in any suitable manner. It is hollow or in the form of a tube. It is open at its front end as designated by numeral 120. Adjacent the open end 120 is an annular outwardly extending bead 121. Rotatably mounted on arm 18 is a hand simulating member 123 which has a hollow rear tubular end 124 rotatably received within the front open end of arm 18. Said portion 124 may be formed with an outwardly extending annular bead 125 received within the bead 121. Thus, member 123 may rotate about the axis of the front end of arm 18. The hand simulating member 123 is fixed to the milk bottle simulating member 22 so as to rotate therewith. The axis of the front end of arm 18 and the rear end of hand simulating member 123 is the axis of the pivot pins 72 of the U-shaped brackets 70, whereby to permit swinging of the bottle 73 as described hereinabove.

The operation of the device will now be described. When the toy is purchased, the glass 20 is filled with milk by removing the cover 20a. The cover is then replaced. The milk will also go into tube 110 and up its coil until it reaches a height in the tube equal to the height of the glass. It will be noted that the glass must be filled in the down position of the glass as at that point the spring 113 will be moved off the tube by a cam pin 102 and the passage through the tube is open. When the spring motor is wound and then permitted to unwind, the crank shaft 100 will rotate and through link 106 will cause arm 19 to swing upwardly. The arm is inclined at an angle which will cause the glass to move to the mouth 16a in the head 16. As the arm starts to move up, cam pin 102 which has engaged spring portion 114 passes beyond said spring and the spring jumps back to shut off the tube 110. The milk in the glass and the tube up to the shut off point will remain there and cannot flow out of the hole 59 in the cover 20a of the glass. When the glass reaches the mouth it will push the head 16 back against the spring 50.

At the same time, the next cam pin 102 will engage spring portion 114 lifting it and opening the tube 110. This tube, it will be recollect, is coiled inside the body to a height above the initial filled up level of the glass. When the tube is now open, the milk will drain out of the glass into the coiled tube due to the fact that the glass is now at a higher level, and the lowering of the level of the milk in the glass will give the appearance of the milk being drunk through the mouth of the toy figure. By the time the hand starts its downward stroke, the glass is emptied and it appeared that the child drank the contents thereof.

As said arm starts to return downwardly, cam 102 rotates past the spring 113, and the tube is again sealed off, and the milk cannot return to the glass therefrom, even when the glass moves below the level of the coil. When the glass approaches its bottommost position, however, the next cam pin 102 raises the spring 113, opens tube 110 and milk will then flow from the tube back into the glass. At the bottom of the stroke, the glass comes down on disc 64 and the lever 61 down against spring 66 causing the milk bottle to swing downward. It therefore appears that the milk returning to the glass 20 is flowing from the bottle.

This cycle is repeated with the glass emptying

7
at the top of the stroke and refilling at the bottom of the stroke until the spring motor is run down.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to protect by Letters Patent:

1. A toy comprising a base, a table simulating member on said base, a chair simulating member on said base and in back of the table simulating member, a toy figure comprising a body simulating member seated on the chair simulating member, a head pivoted on said body, a forearm simulating member pivoted to the body and projecting over the top of the table simulating member, a glass held by the forearm, a spring motor within the body simulating member, a crank shaft adapted to be rotated by the spring motor and a link interconnecting the crank shaft with the forearm simulating member, whereby rotation of said shaft will oscillate said forearm simulating member about its pivotal connection to the body from a down position at the table member to an up position at the head, a normally opened tube in the body and passing through the forearm and connected to the bottom of the glass, and means controlled by movement of the arm to constrict said tube during part of the movement of the arm between its up and down position, and to release said tube at its up and down position.

2. A toy comprising a base, a table simulating member on said base, a chair simulating member on said base and in back of the table simulating member, a toy figure comprising a body simulating member seated on the chair simulating member, a head pivoted on said body, a forearm simulating member pivoted to the body and projecting over the top of the table simulating member, a glass held by the forearm, a spring motor within the body simulating member, a crank shaft adapted to be rotated by the spring motor and a link interconnecting the crank shaft with the forearm simulating member, whereby rotation of said shaft will oscillate said forearm simulating member about its pivotal connection to the body from an upward position to a downward position, a cover on said glass formed with an opening, a tube communicating with the lower end of said glass and having a volume at least equal to that of the glass, and passing through said forearm simulating member and into the body simulating member, and extending upwardly to a level above the level of the top of the glass when said forearm simulating member is in its downward position, spring means to constrict the tube to close the passage therein, and cam means on said crank shaft for lifting said spring means and opening said tube when said forearm simulating member is at the ends of its oscillating strokes.

3. A toy comprising a base, a table simulating member on said base, a chair simulating member on said base and in back of the table simulating member, a toy figure comprising a body simulating member seated on the chair simulating member, a head pivoted on said body and having a

10 mouth, a forearm simulating member pivoted to the body and projecting over the top of the table simulating member and oscillatable from its position above the table to the mouth of the head, a glass held by the forearm, a spring motor within the body simulating member, a crank shaft adapted to be rotated by the spring motor and a link interconnecting the crank shaft with the forearm simulating member, whereby rotation of said shaft will oscillate said forearm simulating member about its pivotal connection to the body from an upward position to a downward position, a cover on said glass formed with an opening, a tube communicating with the lower end of said glass and having a volume at least equal to that of the glass, and passing through said forearm simulating member and into the body simulating member, and extending upwardly to a level above the level of the top of the glass when said forearm simulating member is in its downward position, spring means to constrict the tube to close the passage therein, and cam means on said crank shaft for lifting said spring means and opening said tube when said forearm simulating member is at the ends of its oscillating strokes, the upper end of the tube being open.

20 4. A mechanical toy comprising a toy figure, said toy figure comprising a body simulating portion, and a head simulating portion, an arm simulating portion pivoted to said body simulating portion, a glass mounted on said arm, means for oscillating said arm up to the head and down away from the head, a normally open tube connected to the lower end of the glass and extending 30 into said body to a point above the level of the top of the glass when said glass is down, releasable closing means to close said tube, and means controlled by movement of the oscillating arm to release said closing means at the upper and lower ends of the stroke of said oscillating arm to respectively permit the flow of liquid out of the glass and to permit the flow of liquid into the glass, said tube having a volume at least as great as said glass.

35 5. A mechanical toy comprising a toy figure, said toy figure comprising a body simulating portion, and a head simulating portion, an arm pivoted to said body simulating portion, a glass mounted on said arm, means for oscillating said arm up to the head and down away from the head, a normally open tube connected to the lower end of the glass and extending into said body to a point above the level of the top of the glass when said glass is down, releasable closing means to close said tube, means controlled by movement of the oscillating arm to release said closing means at the upper and lower ends of the stroke of said oscillating arm, a second arm on said body simulating member, a bottle simulating member, attached to said second arm, means to mount said bottle simulating member for pivotal movement, and means controlled by movement of said first arm for oscillating said bottle simulating member, when said arm moves down, said tube having a volume at least as great as said glass.

40 6. A mechanical toy comprising a toy figure, said toy figure comprising a body simulating portion, and a head simulating portion, an arm simulating portion pivoted to said body simulating portion, a glass mounted on said arm, means for oscillating said arm up to the head and down away from the head, a normally open tube connected to the lower end of the glass and extending 45 into said body to a point above the level of the top of the glass when said glass is down, releasable closing means to close said tube, means controlled by movement of the oscillating arm to release said closing means at the upper and lower ends of the stroke of said oscillating arm, a second arm on said body simulating member, a bottle simulating member, attached to said second arm, means to mount said bottle simulating member for pivotal movement, and means controlled by movement of said first arm for oscillating said bottle simulating member, when said arm moves down, said tube having a volume at least as great as said glass.

50 7. A mechanical toy comprising a toy figure, said toy figure comprising a body simulating portion, and a head simulating portion, an arm simulating portion pivoted to said body simulating portion, a glass mounted on said arm, means for oscillating said arm up to the head and down away from the head, a normally open tube connected to the lower end of the glass and extending 55 into said body to a point above the level of the top of the glass when said glass is down, releasable closing means to close said tube, means controlled by movement of the oscillating arm to release said closing means at the upper and lower ends of the stroke of said oscillating arm, a second arm on said body simulating member, a bottle simulating member, attached to said second arm, means to mount said bottle simulating member for pivotal movement, and means controlled by movement of said first arm for oscillating said bottle simulating member, when said arm moves down, said tube having a volume at least as great as said glass.

60 8. A mechanical toy comprising a toy figure, said toy figure comprising a body simulating portion, and a head simulating portion, an arm simulating portion pivoted to said body simulating portion, a glass mounted on said arm, means for oscillating said arm up to the head and down away from the head, a normally open tube connected to the lower end of the glass and extending 65 into said body to a point above the level of the top of the glass when said glass is down, releasable closing means to close said tube, means controlled by movement of the oscillating arm to release said closing means at the upper and lower ends of the stroke of said oscillating arm, a second arm on said body simulating member, a bottle simulating member, attached to said second arm, means to mount said bottle simulating member for pivotal movement, and means controlled by movement of said first arm for oscillating said bottle simulating member, when said arm moves down, said tube having a volume at least as great as said glass.

the top of the glass when said glass is down, releasable closing means to close said tube, and means controlled by movement of the oscillating arm to release said closing means at the upper and lower ends of the stroke of said oscillating arm, said tube having a volume at least as great as said glass and being open at its upper end.

7. A mechanical toy comprising a toy figure, said toy figure comprising a body simulating portion, and a head simulating portion, an arm simulating portion pivoted to said body simulating portion, a glass mounted on said arm, means for oscillating said arm up to the head and down away from the head, a normally open tube connected to the lower end of the glass and extending into said body to a point above the level of the top of the glass when said glass is down, releasable closing means to close said tube, and means controlled by movement of the oscillating arm to release said closing means at the upper and lower ends of the stroke of said oscillating arm, said tube having a volume at least as great as said glass and being open at its upper end, said head simulating member being pivoted to the body simulating member, spring means to tilt said head simulating member in one direction, and said glass being adapted to contact said head simulating member and tilt the same against the spring means.

8. A mechanical toy comprising a toy figure having a body, a head on said body, an arm pivoted to said body, a glass on said arm, a crank shaft on said body, means to rotate said crank shaft, means on said crank shaft to oscillate said arm up to the head and down away from said head, a flexible tube connected to the lower end of the glass and extending to a level above the height of the glass when said arm is in its down position, said tube having a volume at least as great as said glass and being open at its upper end, spring means to constrict said tube, and means on said crank shaft to release said constricting means as said arm approaches the ends of its oscillating strokes.

9. A mechanical toy comprising a toy figure having a body, a head on said body, an arm pivoted to said body, a glass on said arm, a crank shaft on said body, means to rotate said crank shaft, means on said crank shaft to oscillate said arm up to the head and down away from said head, a flexible tube connected to the lower end of the glass and extending to a level above the height of the glass when said arm is in its down position, said tube having a volume at least as great as said glass and being open at its upper end, spring means to constrict said tube, and means on said crank shaft to release said constricting means as said arm approaches the ends of its oscillating strokes, and a cover on the glass formed with a hole.

10. A mechanical toy comprising a toy figure having a body, a head on said body, an arm pivoted to said body, a glass on said arm, a crank shaft on said body, means to rotate said crank shaft, means on said crank shaft to oscillate said arm up to the head and down away from said head, a flexible tube connected to the lower end of the glass and extending to a level above the height of the glass when said arm is in its down position, said tube having a volume at least as great as said glass and being open at its upper end, spring means to constrict said tube, and means on said crank shaft to release said constricting means as said arm approaches the ends of its oscillating strokes, a toy table in front of

said toy figure and a pivoted lever attached thereto, spring means to raise said lever, a rod pivoted to said lever and carrying a disc at its upper end, and said glass being adapted to contact said disc and depress said lever against said spring when the glass is lowered, a milk bottle and means connecting the milk bottle with the lever to move said milk bottle upon depressing said lever.

- 10 11. A mechanical toy comprising a toy figure having a body, a table in front of said body, a head on said body, an arm pivoted to said body, a glass on said arm, a crank shaft on said body, means to rotate said crank shaft, means on said crank shaft to oscillate said arm up to the head and down away from said head, a flexible tube connected to the lower end of the glass and extending to a level above the height of the glass when said arm is in its down position, said tube having a volume at least as great as said glass and being open at its upper end, spring means to constrict said tube, and means on said crank shaft to release said constricting means as said arm approaches the ends of its oscillating strokes, 25 a pivoted lever attached to said table, spring means to raise lever, a rod pivoted to said lever and carrying a disc at its upper end, and said glass being adapted to contact said disc and depress said lever against said spring when the glass is lowered, a second arm on said body, a pivoted milk bottle carried by said second arm, and a link interconnecting said lever with said milk bottle, whereby depressing said lever will tilt said bottle.
- 30 12. A mechanical toy comprising a toy figure having a body, a toy table in front of said toy body, a head on said body, an arm pivoted to said body, a glass on said arm, a crank shaft on said body, means to rotate said crank shaft, means on said crank shaft to oscillate said arm up to the head and down away from said head, a flexible tube connected to the lower end of the glass and extending to a level above the height of the glass when said arm is in its down position, said tube having a volume at least as great as said glass and being open at its upper end, spring means to constrict said tube, and means on said crank shaft to release said constricting means as said arm approaches the ends of its oscillating strokes, 35 a pivoted lever attached to the underside of said toy table, spring means to raise said lever, a rod pivoted to said lever and carrying a disc at its upper end, and said glass being adapted to contact said disc and depress said lever against said spring when the glass is lowered, a second arm on said body, a pivoted milk bottle carried by said second arm, and a link interconnecting said lever with said milk bottle, whereby depression of said lever will tilt said bottle, said head being pivoted to said body, 40 spring means to tilt said head forwardly, and said glass being adapted to tilt the head back.
- 45 13. A mechanical toy comprising a base, a toy table on the base, a toy chair on the base and in back of the table, a toy figure on the chair and including right and left arms disposed over the table, a glass on one arm, a reservoir in the body connected with the glass, a toy milk bottle on the other arm, means to pivot the milk bottle to the table, means for oscillating said one arm up and down, and means controlled by the first means for oscillating the bottle about its pivot, and means controlled by movement of the first arm to control movement of liquid from the glass to the 50 reservoir and from the reservoir to the glass.
- 55 60 70

11

14. A mechanical toy comprising a base, a toy table on the base, a toy chair on the base and in back of the table, a toy figure on the chair and including right and left arms disposed over the table, a glass on one arm, a toy milk bottle on the other arm, means to pivot the milk bottle to the table, means for oscillating said one arm up to the head of the figure and down to the table, and means controlled by the first means for oscillating the bottle about its pivot upon moving said arm down to the table, a resilient tube communicating with the glass, and means for constricting the tube when the arm moves up, releasing the tube when the arm is fully up, restricting the tube when the arm starts down, and releasing the tube when the arm is fully down.

15. A toy comprising a base, a table simulating member on said base, a chair simulating member on said base and in back of the table simulating member, a toy figure comprising a body simulating member seated on the chair simulating member, a head pivoted on said body member and having a mouth, a forearm simulating member pivoted to the body member and projecting over the top of the table member and oscillatable from its position above the table upwardly to the mouth of the head member, a glass held by the forearm member, a motor within the body simulating member, a crankshaft adapted to be

12

rotated by the motor, and a link interconnecting the crankshaft with the forearm simulating member, whereby rotation of said shaft will oscillate said forearm simulating member about its pivotal connection to the body member, a cover on said glass formed with an opening, a tube connected at one end to the lower end of the glass and passing through said forearm simulating member and into the body simulating member and having a volume at least equal to that of the glass, said tube extending upwardly to a level above the level of the top of the glass when said forearm simulating member is in its downward position, and means controlled by movement of the arm to pinch said tube during a part of its movement from down position to up position.

MILTON ADLER.
